UNITED STATES PATENT OFFICE.

CARL J. WRIGHT, OF TOLEDO, OHIO, ASSIGNEE TO DOHERTY RESEARCH COMPANY, OF NEW YORK, N. Y., A CORPORATION OF DELAWARE.

FURNACE.

Application filed May 6, 1921. Serial No. 467,250.

To all whom it may concern:

Be it known that I, CARL J. WRIGHT, a citizen of the United States of America, residing at Toledo, in the county of Lucas, State of Ohio, have invented certain new and useful Improvements in Furnaces; and I do hereby declare the following to be a full, clear, and exact description of the invention, such as will enable others skilled in the art to which it appertains to make and use the same.

This invention relates to furnaces and particularly to furnaces which may be used for melting brass or other non-ferrous metals in crucibles.

Heretofore, so far as applicant is aware, furnaces for melting brass in crucibles have always been heated by coke or anthracite coal, since the temperature required to heat the crucibles to the requisite degree could not be obtained by the use of other fuels. For example, crucible furnaces as formerly constructed were not adapted to develop a sufficiently high temperature from gaseous fuel to properly melt brass in crucibles.

It is an object of this invention to provide a furnace in which gaseous fuel may be employed to heat a crucible in order to melt brass or to perform other metallurgical operations for which crucible furnaces are commonly employed. To this end an important feature of the invention resides in the provision of a chamber constructed to contain a crucible and having regenerator chambers associated with it for pre-heating the air which is used to support the combustion of the fuel in the furnace. In the illustrated apparatus, the crucible chamber comprises a series of compartments each constructed to contain a crucible and is formed by walls projecting inwardly from the opposite ends of the furnace and spaced from the sides of the furnace to provide a regenerator chamber on each side of the crucible chamber. The regenerator chambers are connected with opposite ends of the crucible chamber by passages into which gas is introduced by burners seated in the walls of the furnace.

In accordance with a further feature of the invention the furnace is equipped with means for removing a crucible from it. As shown, such means comprises a hydraulic elevator associated with each of the compartments of the crucible chamber and de-

vices for separately controlling the operation of the elevators.

In the operation of regenerative furnaces, the regenerator chambers are alternately heated by the exhaust gases leaving the furnace and cooled by the air which is introduced into the furnace to support the combustion of the fuel. When the valve for controlling the air and exhaust gases has just been reversed, there is a wide difference in temperature between the exhaust gases and the regenerator through which they pass and a consequent rapid transference of heat from the exhaust gases to the regenerator. As the flow of the exhaust gases through a regenerator continues, however, the temperature of the regenerator is constantly raised so that the difference in temperature between the regenerator and the exhaust gases constantly grows less. Consequently, the rate of transfer of heat from the exhaust gases to the regenerator decreases until a point is reached where the heat transferred to the regenerator in any given interval of time is less than the amount required to heat the quantity of air which is supplied to the furnace during such interval. In order to obtain the maximum efficiency from the regenerators, it is necessary to reverse the controlling valve before the above-mentioned point is reached.

If, on the other hand, the controlling valve of a regenerative furnace is reversed when too small amounts of exhaust gases have been passed through the regenerators, they will be insufficiently heated. The temperature of the furnace will, consequently, be low, since it depends in great measure on the degree to which the air is pre-heated in the regenerators. When the periods between reversals are short a further loss of efficiency is suffered by reason of the time consumed in effecting them.

It is a further object of the invention to provide valve reversing mechanism for regenerative furnaces which will enable the regenerators to be utilized always at their highest efficiency. To this end another important feature of the invention resides in the provision of means for controlling the speed of the operating means for the valve reversing mechanism and, consequently, the intervals of time between the operations of the valve reversing mechanism, in accordance with the rate of supply of fuel to the

furnace. The illustrated construction is such that when the rate of supply of fuel to the furnace is increased or decreased, the speed of operation of the valve reversing mechanism is also increased or decreased to shorten or lengthen, as the case may be, the intervals of time between the reversals of the furnace controlling valve. The means for controlling the rate of supply of fuel to the furnace is so connected with the operating means for the valve reversing mechanism that the intervals of time between the operations of the furnace controlling valve are made shorter or longer in accordance as the rate of supply of fuel to the furnace is increased or decreased, in such a ratio that, regardless of variations in the rate of supply of fuel to the furnace, the reversals of the flow of air and exhaust gases through the regenerator chambers take place when the temperature of the regenerator chambers is substantially that at which they operate with the maximum efficiency.

A further feature of the invention contemplates the use of an electric motor for operating the valve reversing mechanism, a valve for controlling the rate of supply of fuel to the furnace, and a rheostat associated with the valve and arranged to interpose more or less resistance in the motor circuit in accordance as the valve is moved toward closed or fully opened position.

Other objects and features of the invention will appear as the description proceeds and will be pointed out in the appended claims.

In the drawings which illustrate a preferred embodiment of the invention;

Fig. 1 is a view in plan of a crucible furnace and valve mechanism for reversing the flow of air and exhaust gases through it, the furnace being shown in section;

Fig. 2 is a longitudinal sectional elevation of the furnace taken substantially on the line 2—2 of Fig. 1;

Fig. 3 is a transverse sectional elevation of the furnace taken substantially on the line 3—3 of Fig. 2;

Fig. 4 is a view of the valve reversing mechanism in side elevation;

Fig. 5 is an elevation of the valve reversing mechanism taken on the line 5—5 of Fig. 4.

Fig. 6 is a view similar to Fig. 4, but showing the cam members of the valve reversing mechanism as having been rotated through nearly 180° from the positions occupied by them in Fig. 4; and,

Fig. 7 is a detail view of the rear valve reversing devices showing them in the positions which they occupy just subsequent to the reversal of the valves.

The illustrated construction comprises a furnace 10 supported by walls 12. The floor 14 of the furnace is upheld between the

walls 12 by double angle irons 16 which have their ends seated in the walls 12 and their central portions supported on a wall 18 which is disposed longitudinally of and beneath the furnace 10.

Manifestly, the furnace 10 may be made in various forms. As shown, however, the outer wall 20 of the furnace is rectangular in shape and is lined with layers 22 and 24 of refractory material. Projecting inwardly from the end walls of the furnace 10 are walls 26 and 28 spaced from the side walls of the furnace to provide regenerator chambers 30 and 32 which if desired may be filled with the usual loosely piled fire brick or other suitable heat storage elements. The projecting ends 34 and 36 of the walls 26 and 28 are also spaced from the end walls of the furnace so as to leave passages 38 and 40 which connect the regenerator chambers 30 and 32 respectively with the chamber 42 intervening between the walls 26 and 28. In the illustrated construction, the chamber 42 is of a length sufficient to contain a number of crucibles 43 and is divided by transverse bars 44 and oppositely disposed members 45 extending inwardly from the walls 26 and 28 into five compartments each constructed to contain a single crucible. The compartments of the chamber 42 are provided with covers 46.

The main floor 14 of the furnace is shouldered at 47 below the walls 26 and 28 to receive blocks 48 constituting the bottom of the compartments of the chamber 42. In the present practice of heating materials in crucibles, it is customary to lower them into and to lift them from the furnace by means of tongs which engage internally shouldered portions near their tops. The crucibles are sometimes broken in the furnace, thus rendering it impossible to remove them from it by means of the usual tongs. In such cases it is often very difficult to remove the crucibles from the furnace. In order to avoid this objection, the blocks 48 of the present invention are formed with openings 50 tapering downwardly from their upper ends and having seated therein correspondingly shaped heads 52 of vertically disposed elevators 54.

The heads 52 of the elevators 54 are located centrally in the compartments of the chamber 42 so as to receive and support the crucibles 43. As shown, the wall 18 of the furnace is hollowed out at 58 to receive the elevators 54, and arranged vertically in the cavities 58 are rails or the like 60 on which ride rolls 62 carried by the elevators 54. In order to enable the elevators 54 to be raised to lift the crucibles from the furnace, the elevators are formed with depending stems 64 on which are piston heads 66 received in cylinders 68 mounted in the wall 18. The cylinders 68 are pro-

vided above and below the upper and lower ranges of movement of the pistons 66 with openings communicating with pipes 70 and 72 connected with a pipe 74 adapted to contain water or other fluid under pressure. The pipes 70 and 72 may be placed alternately into communication with the pressure pipe 74 and an exhaust pipe 76 by valves 78. From the foregoing it will be understood that the elevators 54 may be independently operated by actuation of the valves 78.

The blocks 48 forming the bottom of the crucible compartments are placed in contact with each other and are cemented together to form a floor common to all of the compartments of the chamber 42. The floor of the chamber 42 is grooved adjacent to the walls 26 and 28 to form troughs 80 on opposite sides of the chamber.

The troughs 80 collect any slag which for any reason such for example, as the breakage of a crucible may be spilled in the crucible chamber and discharge it from the furnace through openings 82 communicating with suitable eduction conduits (not shown).

As already indicated the furnace 10 is particularly adapted to burn gaseous fuel. In the illustrated construction, gas of suitable character, for example, water gas, is introduced into the furnace through burners 84 and 86 located in the ends of the furnace in line with the chamber 42. It will be apparent, therefore, that gas introduced into the furnace through burners 84 and 86 first enters the passages 40 and 38 where it mingles with air from the regenerator chambers 32 and 30 respectively. Two of the burners 84 and 86 are preferably seated in each end of the furnace in superimposed relation. The burners 84 and 86 are supplied with gas by pipes 88 and 90 respectively which in turn are connected with a valve casing 92. The valve casing 92 received gas from a main supply pipe 94 and contains a four-way valve adapted to direct gas selectively to the burners 84 and 86.

Air is introduced into the regenerator chambers 30 and 32 at the ends remote from the passages 38 and 40 by pipes 96 and 98 respectively. The pipes 96 and 98 are in turn connected with a valve casing 100 containing a four-way valve adapted to admit air selectively to the regenerator chambers 30 and 32. The air and gas control valves are connected to a shaft 102 for operation thereby, the arrangement of the valves being such that during certain of the alternating periods of operation of the furnace, gas and air are introduced into the furnace through the burners 84 and pipe 98 respectively, whereas, during the other periods gas and air are introduced into the furnace through the burners 86 and pipe 96 respectively. In the former periods the air is

pre-heated in passing through the regenerator chamber 32 to the passage 40 where it mixes with gas from the burners 84. The combustion of the gas takes place mainly in the chamber 42 for which reason the chamber 42 is sometimes referred to hereinafter as a combustion chamber. The members 45 on the walls 26 and 28 direct the burning gas into close contact with the crucibles 43. The exhaust gases from the combustion chamber 42 pass through the passage 38 into the regenerator chamber 30 and thence through the pipe 96 to the valve casing 100 from which they issue through a pipe 104. During the intermediate periods of the operation of the furnace, air enters the regenerator chamber 30 through the pipe 96, and, after being pre-heated in that chamber, mingles in the passage 38 with gas entering the furnace through the burners 86. The gas is then burned in the combustion chamber 42, and the exhaust gases pass from the chamber through the passage 40 and the regenerator chamber 32 to the pipe 98 which conducts them to the valve casing 100 and pipe 104.

The valve operating shaft 102 is oscillated so as alternately to reverse the valves in the casings 92 and 100 in order to cause gas and air to enter the furnace during alternate periods through the pipes 84—98 and the pipes 86—96. It is essential that the valves be reversed at regular periods, and it is very desirable that the movement of the valves from one position to another, when once initiated, shall be quickly effected.

In the preferred embodiment of the invention, the shaft 102 is journaled for oscillation in a frame 106 adjacent to the furnace 10, and the reversal of the valves is accomplished quickly and at regular intervals by mechanism including arms 108 and 110 (Figs. 4 and 6) fast on the shaft. As shown, the arms 108 and 110 extend downwardly and upwardly respectively from diametrically opposite sides of the shaft 102. Devices are mounted on the frame 106 at one side of the shaft 102 for acting by impact on the arms 108 and 110 to oscillate the shaft 102 so as to reverse the valves.

The arm 108 is operated by a device 112 having on its lower end a bar 114 in the free end of which is a pin 116 arranged to abut against the arm 108. The device 112 is slidably mounted on a supporting bar 118 extending from one end of the frame 106 to the other. A spring 120, attached at one end to an ear 122 (Figs. 4 and 6) on the device 112 and at its other end to a suitable anchor 124 carried by the frame 106 urges the device toward the arm 108.

Co-acting with the arm 110 is an actuating device 126 (Figs. 4 and 7), the upper portion of which is constituted by a bar 128 carrying a pin 130 at its free end in posi-

tion to engage the arm 110. The device 126 is mounted for sliding movement on a bar 132 supported horizontally on the frame 106 in like manner to the bar 118. A spring 5 134 suitably secured to the device 126 and the frame 106 urges the device toward the arm 110.

The devices 112 and 126 are disposed respectively below and above the horizontal 10 plane through the axis of the shaft 102 and are mounted for movement parallel to that plane. The devices are controlled in their operations on the arms 108 and 110 by mechanism including a sleeve 136 loosely mounted 15 on the shaft 102 and carrying cams 138 and 140 arranged to engage rolls 142 and 144 on the devices 112 and 126 respectively. The sleeve 136 and the cams 138 and 140 may be rotated by a worm wheel 146 fixed to the 20 sleeve. Meshing with the worm wheel 146 is a worm 148 on a shaft 150 journaled in the frame 106. The shaft 150 is in turn provided with a worm wheel 152 meshing with a worm 154 on a shaft 156 journaled on the 25 frame 106 at right angles to the shaft 150. The shaft 156 is operated by gearing 158 from the shaft 160 of an electric motor 162 suitably mounted on the frame 106.

The cams 138 and 140 are of like construction 30 and are mounted on the sleeve 136 at angles of approximately 180° to each other (Figs. 4, 6 and 7). Each of the cams comprises a semi-circular peripheral face 164 of substantially 180° in length, a straight 35 face 166 extending inwardly from one end of the peripheral face 164 to a point adjacent to the shaft 102, and a cam face 168 extending from the peripheral face 164 to the base of the straight face 166 adjacent to 40 the shaft 102.

The valve reversing mechanism operates as follows: The cams 138 and 140 are rotated in the direction of the arrows (Figs. 4 and 6) and when the edge 170 at the junction 45 of the straight face 166 and peripheral face 164 of the cam 138 is carried past the roll 142 on the device 112, the device is moved to the left (Fig. 4) by its spring 120 to cause it to impact sharply on the arm 108, thereby moving the arm 108 quickly 50 to the left (Fig. 4) and oscillating the shaft 102 to reverse the position of the valves. In this position of the parts, the roll 144 on the device 126 engages the peripheral face 55 164 of the cam 140 and thus causes the device 126 to be maintained in a position such that the pin 130 is held out of the way of the arm 110 as it moves to the right in response to the movement of the arm 108 to the left. 60 In the continued rotation of the cams 138 and 140, the device 112 is moved to the right by the cam face 168 of the cam 138 to the position shown in Fig. 6, it being apparent from Fig. 6 that the device 112 is moved 65 to fully withdrawn position before the edge

172 of the cam 140 passes from the roll 144 on the actuating device 126. Consequently, when the edge 172 of the cam is moved past the roll 144 on the device 126, thus permitting that device to be operated by the spring 70 134 to engage and actuate the arm 110, the device 112 is held away from the arm 108 to allow unimpeded retrograde movement of the arm 108 to the right as the arm 110 is moved to the left by the device 126. It will 75 be understood, therefore, that the cams 138 and 140 not only control the actuation of the arms 108 and 110 by the devices 112 and 126 respectively, but also that each of such cams by reason of their arrangement and the provision of each with a semi-circular peripheral face of a length of 180° operates, following the operation of the device 112 or 80 126, to move the device out of the way of its co-acting arm 108 or 110 before the next 85 succeeding operation of the other arm. It will, furthermore, be apparent, inasmuch as the devices 112 and 126 operate by impact under the action of the springs 120 and 134 to reverse the valves, that after reverse 90 movement of the valves is initiated, it is very quickly effected so that the time expended in reversing the valves is reduced to a minimum.

It is important that the flow of air and 95 gas to the furnace 10 shall be reversed when the temperature of the regenerators is substantially that at which the furnace operates with the maximum efficiency. In the illustrated construction, this is effected by varying the speed of operation of the motor 162 in accordance with variations in the rate of 100 supply of gas to the furnace. As shown, the rate of supply of gas may be varied by a valve 174 in the main gas supply pipe 94, and connected with the valve 174 is a rheostat 176 interposed in the circuit of the motor 162. The rheostat 176 controls the speed 105 of operation of the motor 162 and inasmuch as the air and gas control valves are reversed at the end of each movement of the cams 138 and 140 through an angle of 180° , the rheostat 176 also governs the length of the intervals 110 between the reversals of the valves. The arrangement of the valve 174 and rheostat 115 176 is such that when the rate of supply of gas to the furnace is increased or decreased, the intervals of time between the reversals of the valves are made shorter or longer in such a ratio that the temperature of the regenerators at the time of the reversals of the valves is caused always to be substantially 120 that at which the regenerators operate with the highest efficiency.

Having described the invention what is 125 claimed is:

1. In a furnace of the class described, an elongated combustion chamber constructed to contain a plurality of crucibles, means for introducing gas into the ends of the chamber, 130

- means for pre-heating the air which is used to support combustion in the chamber, means for reversing the flow of air and gas through the combustion chamber, and devices extending inwardly from the walls of the combustion chamber and acting to direct the burning gas into close contact with the crucibles in the chamber.
2. In a furnace of the class described, walls projecting inwardly from substantially opposite parts of the furnace and arranged to define a centrally located chamber constructed to contain a crucible, said walls being spaced from the adjacent portions of the wall of the furnace to provide regenerator chambers at each side of the first-mentioned chamber and each of the first-mentioned walls having its projecting end spaced from the wall of the furnace to form passages which connect the ends of the central chamber with the regenerator chambers, means for supplying air and fuel to the furnace, and means for periodically reversing the flow of air and exhaust gases through the regenerator chambers.
3. In a furnace of the class described, walls projecting inwardly from opposite sides of the furnace and arranged to define an elongated centrally-located chamber constructed to contain a series of crucibles, said walls being spaced from the other sides of the furnace to provide regenerator chambers at each side of the central chamber and each of the walls having its projecting end spaced from the wall of the furnace to form passages which connect the ends of the central chamber with the regenerator chambers, burners arranged to supply gas to said passages, means for supplying air to the regenerator chambers, and means for periodically reversing the supply of gas and air to the burners and the regenerator chambers respectively.
4. In a furnace of the class described, an elongated chamber comprising a plurality of compartments each constructed to contain a crucible, a movable support located below the central portion of each of the compartments, means for elevating the supports to lift crucibles from the chamber, a floor common to all of the compartments and formed to provide troughs on opposite sides of the supports, said troughs acting to collect slag which may escape from a crucible in any of the compartments so as to enable the slag to be discharged from the chamber, and means for heating the chamber.
5. In a regenerative furnace, valve reversing mechanism, an electric motor for operating said mechanism, a rheostat for controlling the speed of the motor, and means for setting the rheostat in accordance with the rate of supply of fuel to the furnace.
6. In a regenerative furnace, means for supplying fluid fuel and air to the furnace, valves for directing the fuel and air selectively to different parts of the furnace, valve reversing mechanism, an electric motor for operating the valve reversing mechanism, a valve for controlling the rate of supply of fuel to the furnace, and means connected with the last-mentioned valve for controlling the speed of the motor in accordance with the rate of supply of fuel to the furnace.
7. In a regenerative furnace, regenerator chambers, means for controlling the operation of the furnace comprising a valve, valve reversing mechanism, a driving device for operating the valve reversing mechanism, means for varying the rate of supply of fuel to the furnace, and means for increasing or decreasing the speed of operation of the driving device when the rate of supply of fuel is increased or decreased so as to cause the valves to be reversed after the regenerator chambers have been heated by the exhaust gases substantially to the point of highest efficiency.
8. In a regenerative furnace, valve reversing mechanism, means for operating said mechanism, and means for controlling the speed of operation of the operating means in accordance with the rate of supply of fuel to the furnace.
- In testimony whereof I affix my signature.

CARL J. WRIGHT.
